RETRIEVING TOOL

Samuel J. E. Marshall and Lowell M. Wilhoit,
Dallas, Tex., assignors to Otis Engineering Corporation, Dallas, Tex., a corporation of Texas

Application February 27, 1948, Serial No. 11,366

3 Claims. (Cl. 294—86)

1

This invention relates to new and useful improvements in retrieving tools.

One object of the invention is to provide an improved retrieving tool which may be run into a well flow conductor on a flexible line, such as a steel measuring line, and which is arranged to releasably engage a well device, whereby said retrieving tool may be utilized to remove the well device from the bore of the well conductor.

Another object of the invention is to provide an improved retrieving tool having supporting means freely engageable with a well device for removing such device from the well, said supporting means being positively held in engaged position when engaging the well device, whereby possibility of disengagement of the retrieving tool from the well device during the removing operation is reduced.

An important object of the invention is to provide an improved retrieving tool wherein the supporting means is positively held in its engaged position, and wherein said supporting means is constructed and arranged to be positively moved to disengaged position upon movement of actuating means relative to said supporting means.

A further object of the invention is to provide an improved retrieving tool of the character described, wherein the actuating means which moves the supporting elements to disengaged position is normally held inactive by releasable restraining means and is automatically actuated upon release of the restraining means.

Still another object of the invention is to provide a retrieving tool wherein the supporting means is normally urged toward engaging position, and wherein the means urging such supporting means to engaging position is rendered inoperative when the actuating means is moved to cause movement of the supporting means to disengaged position.

A particular object of the invention is to provide a retrieving tool of the character described having supporting means freely engageable with a well device for removing such device from the well, and having actuating means movable on the retrieving tool with respect to the supporting means for positively engaging the supporting means to positively move said supporting means to released position, said actuating means being normally restrained against movement.

A still further object of the invention is to provide an improved tool for retrieving from a well conductor a well device having a mandrel and a gripping mechanism movable on said mandrel, said retrieving tool being adapted to engage

2

the mandrel of the well device whereby force may be applied to said mandrel to release the gripping mechanism from gripping position, said retrieving tool being arranged to engage and support the gripping mechanism to permit removal of the well device from the conductor.

Still another object of the invention is to provide a retrieving tool, of the character described, wherein the supporting element is itself supported, whereby the weight of the well device with which the retrieving tool is engaged is not carried solely by the supporting element.

Another important object of the invention is to provide a retrieving tool, of the character described, wherein the restraining means for normally restraining the actuating means against movement of the supporting element to retracted releasing position includes a frangible element which is fully enclosed within the tool, whereby when said frangible element is fractured the pieces thereof cannot fall into the bore of the well around the well device to interfere with the removal thereof, said frangible element being adapted to fracture under a predetermined strain to release the actuating means, whereby the actuating means may act upon the supporting element to positively move said supporting element to retracted disengaged position to release the retrieving tool from the well device.

Still another object of the invention is to provide an improved retaining member for retaining the fractured frangible element pieces within the tool.

Additional objects and advantages of the invention will be readily apparent from a reading of the following description of a device constructed in accordance with the invention, and reference to the accompanying drawings thereof, wherein:

Figure 1 is a view, partly in elevation and partly in section, of a retrieving tool constructed in accordance with the invention, and showing the same being lowered into a well for engaging a well device.

Figure 2 is a view, partly in elevation and partly in section, of the lower portion of the retrieving tool, showing the retrieving tool moving into supporting engagement with the well device.

Figures 3 and 4 are horizontal cross-sectional views taken on the line 3—3 and 4—4 respectively of Figure 1, and

Figure 5 is a view, partly in elevation and partly in section, of the retrieving tool, showing

the supporting means in disengaged or releasing position.

In the drawings, the numeral 10 designates an elongate body or core which is substantially cylindrical and which is provided with an upwardly extending externally screw-threaded pin 11 at its upper end. The pin is reduced in diameter relative to the external diameter of the core, whereby an upwardly facing annular shoulder 12 is formed at the junction of the body and the pin. The lower end of the core is formed with an external annular flange 13, providing an upwardly facing shoulder or seat 14 at its upper end.

An elongate substantially cylindrical sleeve member 15 is slidably mounted on the core 10, and has the major portion of its bore enlarged as shown at 16 to slide over the flange 13 at the lower end of the core. The upper portion of the bore of the sleeve 15 is slideable on the cylindrical portion of the core. The sleeve is provided with a pair of diametrically opposed longitudinal slots 17 which terminate short of the lower end of the sleeve 15 and extend upwardly substantially throughout the lower half or portion of the length of the enlarged bore of the sleeve. Windows or openings 18 are formed in the sleeve spaced above and in longitudinal alignment with the slots 17 in said sleeve. In addition, the sleeve is preferably provided with fluid by-pass ports 19 which are formed in the wall of the sleeve between the slots 17.

A pair of elongate supporting elements or dogs 20 are disposed diametrically opposite each other within the slots 17 in the sleeve, and are confined at their upper ends between said sleeve and the lower portion of the core 10. Each dog has an upwardly facing hook or engaging element 21 formed at its lower end portion, and is provided near its upper end with an internal downwardly facing shoulder 22 which is adapted to engage and be supported on the seat or shoulder 14 at the upper end of the flange 13 of the core. Above the shoulder 22, the outer surface of each dog is provided with an offset or recess 23 whereby said upper portion of the dog may extend upwardly between the sleeve 15 and the core 10, as best shown in Figure 1. Outwardly extending lugs 24 are formed at the upper end of the dogs and these lugs project outwardly into and are disposed within the windows or openings 18 in the sleeve. The upper portion of each lug is beveled, or tapers downwardly and outwardly, to provide a wedge surface 25 which is adapted to be engaged by the sleeve 15 at the upper edge 18a of the opening or window 18. The offset or recess 23 in the upper portion of each dog is loosely confined within the annular space between the core and sleeve, whereby the dog may undergo a limited longitudinal and lateral motion therebetween.

The lower end of each dog or supporting element is provided with a beveled surface 26 on its outer edge which is adapted to slide upon a corresponding inwardly and downwardly extending inclined surface 27 formed at the lower end of the slots 17 in the sleeve, whereby the dog is movably supported on such inclined surface. The lower inner end portion of each dog is also formed with a slight bevel 28 to permit the dog to slide readily over a well device A, as will be hereinafter more fully explained.

It will be seen, therefore, that the supporting elements or dogs 20 are movably confined within the slots 17, and that outward displacement of said dogs from the slots is prevented by the en-

gagement of the lower end of each dog with the inclined surface 27 at the lower end of each slot and the engagement of the upper portion of the dog with the sleeve between the upper end of the slot 17 and the window 18, while inward displacement of the dog is prevented by the engagement of the inner portion of the dog with the core 10.

A push ring 30 is slidable in the annular space between the sleeve and the core above the dogs, and is adapted to engage the upper ends of said dogs. A helical coiled spring 31 is also positioned within the annular space between the enlarged bore 16 of the sleeve and the core 10 and is confined between the push ring 30 and a transversely extending pin 32 mounted in said core and movable therewith in the enlarged bore 16 of the sleeve. With the parts of the retrieving tool in the position shown in Figure 1, the spring 31 is under compression and acts downwardly upon the push ring 30 to urge the dogs 20 downwardly within the slots 17 in the sleeve, thus causing the lower ends of the dogs to be moved inwardly on the inclined surfaces 27 at the lower ends of said slots. The lower ends of the dogs may, however, move upwardly and outwardly along such inclined surface upon being forced upwardly against the force exerted by the spring. It will be seen, therefore, that the dogs are constantly resiliently urged toward engaging and supporting position by the action of the spring and push ring 30, when the parts are in the position shown in Figure 1.

An elongate sub or connecting member 35, having a depending annular skirt 36, is screw-threaded onto the pin 11 at the upper end of the core. The skirt 36 surrounds and is spaced from the upper cylindrical portion of the core and is positively positioned longitudinally of the sub by the engagement of the sub with the shoulder 12 at the upper end of the core. The upper portion of the sub is reduced in diameter and is connected, by means of a screw-threaded pin 37, to a suitable raising and lowering mechanism 38, which may consist of link jars, a weight member or sinker bar, and a socket member (not shown) by means of which the retrieving tool is connected to a flexible steel measuring line or cable (not shown), whereby the retrieving tool may be lowered into and removed from the well flow conductor. A set screw 39 threaded through the side of the sub and engaging the upper end of the pin 11 of the core prevents the sub from being loosened or accidentally removed from the core.

A helical coiled spring 40 is positioned in the annular space between the skirt 36 of the sub and the core 10, and has its upper end engaging the underside 35a of the sub and its lower end acting upon the upper end of the sleeve 15, as is clearly shown in Figures 1 and 5. This spring tends to urge the sleeve 15 downwardly, from the position shown in Figure 1 to the position shown in Figure 5, whereby the wedge surfaces 25 at the upper ends of the dogs 20 are engaged by the downwardly facing edges 18a of the sleeve at the upper end of the slots or windows 18 in said sleeve to swing the upper ends of the dogs inwardly as shown in Figure 5. Since the downwardly facing shoulders 22 on the inner side of the dogs is narrower than the upwardly facing shoulder 14 on the core or body 10, the dogs will pivot, at the junction of the downwardly facing shoulder 22 with the inside of the dogs, upon the outer edge of the core shoulder 14, whereby such inward movement of the upper ends of the dogs swings the lower ends of the dogs outwardly.

from engaging position, as clearly shown in Figure 5. Downward movement of the sleeve 15 with respect to the sub first moves the dogs downwardly until the shoulder 22 engages the upwardly facing seat 14 on the sub to stop further downward movement of the dogs. Engagement of the edge 18a of the sleeve at the upper end of the windows 18 with the wedge surfaces 25 at the upper end of the dogs then swings the upper ends of the dogs inwardly to the position shown in Figure 5, whereby the lower ends of the dogs are swung outwardly from engaging position to the retracted or disengaged position shown in Figure 5.

For releasably holding the sleeve 15 in its uppermost position, shown in Figure 1, wherein the dogs or supporting elements 20 are permitted to move to their engaging position, a frangible member or pin 41 is provided in a transverse hole 42 extending diametrically through both the sleeve 15 and the core 10, as clearly shown in Figure 1. The upper peripheral portion of the sleeve is reduced slightly in diameter, and a cap or cover ring 43, having an inwardly directed annular flange 44 at its upper end, surrounds the reduced upper portion of the sleeve 15 and confines the pin 41 in the transverse hole 42. The inwardly directed flange 44 engages over and is supported upon the upper end of the sleeve, being held securely in place thereagainst by the helical spring 40. Thus, when the pin 41 is sheared, in the manner which will be hereinafter explained, the sheared portions of the pin are prevented from falling out of the hole 42 by the cap ring 43.

Diametrically opposed openings 45 are formed in the lower portion of the cap ring to permit insertion of a new shear pin into the hole 42 after the previous pin has been sheared. After the new shear pin has been installed, the cap ring is turned through approximately 90 degrees to position the openings 45 out of alignment with the shear pin 41, whereby the shear pin is positively retained in the transverse hole 42 by said cap ring.

In use, the tool is assembled as shown in Figure 1 and connected to the flexible line lowering and raising mechanism by means of which it may be lowered into the well flow conductor T. It will be noted that, with the sleeve 15 held in its uppermost normal position by the shear pin 41, as illustrated in Figure 1, the dogs 20 may each independently undergo a limited longitudinal movement in the slots 16, since the dogs are not connected together. The dogs are normally urged downwardly within the slots 16 by the compressive force of the spring 31, the lower ends of said dogs having the supporting element 21 thereon being urged inwardly into the bore of the sleeve 15 by the inclined surfaces 27 at the lower ends of the slots.

Any suitable well device A may be removed from the conductor T by means of the tool herein described, and the type shown is one such as is illustrated and described in the patent to H. C. Otis, No. 1,972,791, issued September 4, 1934, and includes a mandrel 50 having a slip assembly slidably mounted thereon. The slip assembly includes a slip carrier 51 which is in the form of a sleeve slidable on the mandrel and having an external annular flange 52 at its upper end.

The sleeve 15 and the dogs 20 of the retrieving tool may be passed downwardly over the flange 52, so that the flange enters the bore of the sleeve and moves upwardly between the dogs until the shoulder at the lower end of the flange is moved

above the supporting projections or hooks 21 at the lower end of the dog, whereby the well device is suspended from the retrieving tool.

The bore of the sleeve 15 of the retrieving tool is preferably made of such a diameter that it slides over and fits rather closely about the flange 52 of the well device, and thus forms an inverted receptacle or bowl for receiving the upper end of the well device. The flange 52 is, therefore, confined against any substantial lateral movement within the sleeve 15, and it is only necessary that the hook or projection 21 on one of the dogs engage under the shoulder at the lower end of the flange to suspend the well device, although engagement of both dogs is preferable. It will, therefore, be seen that only a single dog is actually required for successful operation of the retrieving tool. Furthermore, since the dogs are each movable independently of the other, should one of the dogs be rendered inactive for any reason, as by becoming stuck in an inoperative position because of the presence of sand or other extraneous matter, or in the event the lower portion and supporting projection or hook of one of the dogs be broken off, the other dog may nevertheless function to engage and support the well device.

Slips 53 are movably connected to and depend from the carrier 51 of the well device A and are expandable into gripping engagement with the bore wall of the tubing or conductor T upon upward movement of the mandrel with respect to said slips, as is clearly set out in the aforesaid Otis Patent, 1,972,791. It will readily be seen, therefore, that when the sleeve 15 and projections or hooks 21 of the supporting dogs have been moved downwardly over the upper end of the well device until the projections or hooks are positioned below the flange 52, the mandrel 50 may be engaged by the lower end of the core 10 of the retrieving tool to force the mandrel downwardly and permit the gripping slips to move to retracted position, whereupon the well device is supported upon the projections or hooks 21 of the retrieving tool and may be lifted upwardly from the well tubing thereby.

When removing the well device from the well tubing, the retrieving tool is lowered over the upper end of the well device until the bevels 28 on the inner lower end of the dogs engage the upper end of the flange 52 on the slip carrier of the well device. Continued downward movement of the retrieving tool moves the dogs upwardly within the slots 17 to permit the hook elements or projections 21 to move outwardly and down past the flange, as illustrated in Figure 2. It is to be noted that, when the hook elements have moved below the flange 52, the lower end of the core 10 of the retrieving tool will engage the upper end of the mandrel 50 before the lower end of the sleeve 15 engages the enlarged flange 51a of the slip carrier. Thus, the mandrel 50 may be driven downwardly, to release the slips 53 connected to the slip carrier, by downward blows imparted to the mandrel through the core 10.

When the slips have been released, the hooks or projections 21 on the dogs will engage under the flange 52, to permit lifting the slip carrier, slips and mandrel of the well device A upwardly within the well tubing. In this position, the beveled lower ends 26 of the dogs engage and ride downwardly and inwardly on the inclined surfaces 27 at the lower ends of the slots 17 in the sleeve. Thus, positive engagement of the

hooks or projections 21 with the well device is assured, and the well device may be readily lifted and removed from the well tubing.

It may sometimes occur that the well device A becomes stuck in the well tubing for some reason, whereby the slips may not be retracted in the manner just described. In such event, the retrieving tool may be released from its engagement with the slip carrier by pulling or jarring upwardly with the running mechanism to fracture or shear the pin 41. When the pin 41 has been sheared, the spring 49 will immediately and automatically move the sleeve 15 downwardly with relation to the core 10. This downward movement of the sleeve causes the edges 18a of the windows 18 to engage the upper ends of the dogs and move the dogs downwardly with respect to the core until the shoulders 22 engage the seat 14 on the core. A continued downward movement of the sleeve causes the edges 18a to engage the wedge surfaces 25 to swing the upper ends of the dogs inwardly to the position shown in Figure 5, and thus swing the lower ends of the supporting dogs outwardly from engagement with the flange 52 of the well device. In such position, the hooks or projections 21 on the dogs do not project into the bore of the sleeve 15 and the entire retrieving tool may be withdrawn from the well.

It will be noted that such downward movement of the sleeve 15 moves the dogs 20 downwardly until the shoulders 22 engage against the seat 14 on the core. In this position, the spring 31 has no further effect upon the dogs. Furthermore, since the spring is confined between the cross pin 32 and does not act upon the sleeve 15, the spring 31 is rendered inactive and the downward movement of the sleeve is not resisted or affected by such spring. The spring 40 thus positively and automatically moves the sleeve 15 downwardly until the edge 18a of the sleeve at the upper end of the windows engages the wedge surface 25 at the upper ends of the dogs and positively moves the dogs to non-engaging retracted position.

Downward movement of the sleeve 15 is limited by engagement of the upper ends of the slots 17 with the upwardly facing shoulders 23a at the lower end of the offsets or recesses 23 in the outer surface of the upper ends of the dogs, said dogs being supported upon the seat 14 at the upper end of the flange 13 of the core.

From the foregoing, it will be seen that a retrieving tool has been provided which has dogs or supporting elements thereon which are independently and individually movable through a limited distance longitudinally and laterally within slots 17 formed in the sleeve 15, and which are normally urged inwardly toward engaging position by the inclined surfaces 27 at the lower ends of the slots and the action of the spring 31 upon the upper ends of the dogs. The inclined surfaces 27 tend to hold the hooks or projections 21 on the lower ends of the dogs in tight engagement with the retrieving connection, such as the flange 52, on the well device which is engaged by the retrieving tool. Any upward pull imparted to the sleeve 15 will tend to move the hooks further inwardly to increase their gripping action on the flange and assure that engagement with such flange is maintained. Furthermore, the portion of the sleeve 15 below the slots and inclined surfaces 27 provides additional support for the dogs 20, so that the entire

weight of the well device is not carried by the dogs alone, but by both the dogs and sleeve.

It will also be seen that the hooks or projections 21 of the dogs are quickly and automatically moved to disengaged position when the shear pin 41 is fractured and the sleeve is moved downwardly with relation to the core 10 by the spring 40.

It will particularly be noted that the provision of the wedge surfaces 25 at the upper ends of the dogs and the pivoting of the dogs on the outer edge of the shoulder 14 on the core provide for positive retraction of the dogs from engaging or supporting position when the edge 18a of the sleeve at the upper end of the windows 18 in the sleeve engages and moves downwardly along said wedged surface.

The foregoing description of the invention is explanatory only, and changes in details of the construction illustrated may be made by those skilled in the art, within the scope of the appended claims, without departing from the spirit of the invention.

What we claim and desire to secure by Letters Patent is:

1. A retrieving tool for retrieving well devices having a mandrel and a gripping mechanism with a flanged carrier slidable on the mandrel, said retrieving tool including, a core, a sleeve movable on said core and having an elongate slot therein with an inwardly and downwardly inclined surface at the lower end of said slot, a supporting element carried by said sleeve with its lower end extending in the slot and movable longitudinally with relation to said core and sleeve, resilient means on the core normally urging said supporting element longitudinally into engagement with the inclined surface at the lower end of the slot for moving the lower end of said supporting element into supporting position, said sleeve being arranged to telescope over the upper end of the flanged carrier of the well device to hold said carrier flange in position to be supported by the supporting element, means on the lower end of the core within the sleeve for engaging the upper end of the mandrel of the well device for applying force downwardly thereto while the supporting element is disposed in supporting position below the flange of the carrier whereby the mandrel may be moved downwardly with respect to the gripping mechanism to permit the well device to be released and removed from the well, a downwardly facing stop shoulder on the inner side of the supporting element adjacent the core, an upwardly facing stop shoulder on the lower end of the core normally spaced below and positioned to be engaged by the downwardly facing stop shoulder on the supporting element for limiting downward movement of the supporting element with respect to the core, wedge means at the upper end of the supporting element arranged to be engaged by the sleeve upon downward movement of the sleeve with respect to the core to move the supporting element to releasing position, and releasable means for normally preventing movement of the sleeve relative to the core.

2. A retrieving tool including, a core, a sleeve movable on said core and extending below the core and forming a bowl open at the bottom adapted to be placed over a well device in a well flow conductor, said sleeve having spaced longitudinal slots therein with inclined surfaces at the lower ends of said slots, supporting members

loosely confined between said core and sleeve and each independently movable longitudinally and laterally with relation to said core and sleeve and each having its lower end extending in one of the slots, resilient means carried by the core normally urging said supporting members longitudinally of the slots into engagement with the inclined surfaces at the lower ends of the slots, for moving the lower ends of said supporting members into supporting position, a downwardly facing stop shoulder on each supporting member, an upwardly facing stop shoulder on the core normally spaced below the stop shoulders on the supporting members and positioned to be engaged by the downwardly facing stop shoulders of the supporting members for limiting downward movement of said supporting members with respect to the core, wedge means at the upper end of each of the supporting members, means on the sleeve arranged to engage the wedge means of the supporting members upon downward movement of the sleeve with respect to the core to move the supporting members to releasing position, and releasable means for normally preventing movement of the sleeve relative to the core.

3. A retrieving tool including, an elongate core having an upwardly facing stop shoulder near its lower end, an elongate tubular sleeve slidable on the core and extending below the core and forming a bowl open at its lower end adapted to be placed over a well device in a well conductor, said sleeve having spaced elongate longitudinal slots formed therein extending below the lower end of the core and each having an inclined surface at its lower end, supporting elements loosely confined between said core and sleeve and each movable longitudinally and laterally independently of the other and with relation to the core and sleeve, the lower ends of said supporting elements being movable into and out of supporting position, resilient means carried by the core and acting upon the supporting elements to normally urge said supporting elements longitudinally of the slots into engagement with the inclined sur-

10

5 face at the lower end of said slots for moving the lower end of the supporting elements into supporting position, a downwardly facing shoulder on each of the supporting elements normally spaced from the upwardly facing shoulder at the lower end of the core and arranged to engage the shoulder on the core for limiting downward movement of the supporting elements with respect to the core, wedge means at the upper end of each supporting element, engaging means on the sleeve arranged to engage the wedge means at the upper end of the supporting elements to move the supporting elements downwardly until the shoulders on the supporting elements engage the shoulder on the core to stop further downward movement of the supporting elements, said engaging means then acting upon the wedge at the upper end of the supporting elements to swing the lower end of the supporting elements to releasing position, resilient means carried by the core and engaging the sleeve and normally urging the sleeve downwardly with respect to the core, and releasable means initially restraining the sleeve in an elevated position with respect to the core and preventing downward movement of the sleeve relative to the core, said releasable means being releasable to permit downward movement of the sleeve relative to the core with respect to the sleeve, such downward movement of the sleeve then causing the supporting elements to be moved to releasing position.
